UNITED STATES PATENT OFFICE

JOHN J. CAVAGNARO, OF RIDGEWOOD, NEW JERSEY

PRESS

Application filed February 5, 1929. Serial No. 337,631.

My invention relates to a press. One of the numerous uses for which a press in accordance with my invention is adapted is for embossing coated fabrics, leather, paper and the like. Such a press is shown herein for illustrating the principle of the invention and affording an understanding thereof, but not for limitation.

I find that the movement of the sliding platen or platens of a press such as an embossing press can be advantageously divided or separated into three parts or phases, namely: maximum opening movement; the free movement of the working stroke during which the feeding is accomplished; and the final closing movement with a dwell for pressing. The maximum opening is required only occasionally and when the press is at rest, as for affording access for making changes of platens and the like; the stroke required in operation, as in embossing work, may be considerably less than such maximum opening, but should be sufficient to permit the feeding of the fabric or other work forward in step-by-step movement, and during the major part of which movement the sliding platen moves freely so that the only power required is that needed to lift such platen; and the final closing stroke, with a dwell for applying the pressure, preferably hydraulic pressure, can be through a very short distance.

In accordance with my invention, preferably manually operated means are provided for securing the maximum opening movement of the press at the occasional intervals when same is required, as for changing dies. Also, provision is made for accomplishing the lesser movement of the press elements to permit the feeding of the work by light, rapidly operated means, preferably mechanical means, not requiring much power, during operation whereof the powerful hydraulic closing means is completely out of operation; and the latter comes into operation only after the press has already been almost closed, this requiring very little travel of the hydraulic closing means and a relatively small quantity of the water, oil, or other liquid used in its operation, and correspondingly

low investment in and space needed for pumps and accumulators.

In the accompanying drawings of an illustrative embodiment of my invention, Fig. 1 is a front elevation with parts broken away. In this view, the sliding press bed or platen is at the top of its mechanical working stroke ready for the application of hydraulic pressure.

Fig. 2 is a rear elevational view.

Fig. 3 is a rear elevation partly in section, taken on the line 3—3 of Fig. 4. In this view, the sliding platen is shown at its lowest position, as for changing matrices, etc.

Fig. 4 is a horizontal section on line 4—4 of Fig. 1 with the cover of the gear train box partly broken away.

Fig. 5 is a section on substantially the line 5—5 of Fig. 4 and showing also a partly broken away portion of the sliding platen.

Fig. 6 is a section on substantially the line 6—6 of Fig. 4. The position of parts in this view is the same as in Fig. 2.

Fig. 7 is a section on approximately the line 7—7 of Fig. 4, and

Fig. 8 is a section on approximately the line 8—8 of Fig. 7.

The press illustrated is a conventional 4-column platen press, having a base 10 provided with guide columns 12 to which is secured the head 14. The sliding platen 16 slides on columns 12, the steam platens 18 and 20 may be secured to the press head 14 and sliding platen 16 respectively. Plates 18 and 20 carry the usual suitably engraved matrices for embossing the work 21 and may be heated and/or cooled, if desired, in any of the usual manners.

The means shown for producing free lifting and lowering movement of the sliding platen 16 to permit feeding of the work comprise cams, preferably 4 in number, designated 22, 24, 26 and 28, each arranged under a corner of the sliding platen 16, and making rolling contact therewith through rollers 30. The cam drive is obtained as shown, through the drive pinion 32, gear 34, clutch 36 and shaft 38, driving cam shaft 40, at one end of the press bed, through bevel gears 42 and 44, from which the parallel cam shaft 46

100

at the opposite end of the press bed is driven through the connecting shaft 48, and bevel gears 50, 52, and 54, 65. With this arrangement, the pair of cams 26 and 28 turns with shaft 40 in opposite direction from the pair of cams 22 and 24 on shaft 46 and, with such arrangement, the respective pairs of cams are made respectively right and left handed, so as to produce identical rise and fall of the press bed at the several corners.

The cam relief at H (Fig. 7) is preferably only sufficient to produce press opening movement sufficient to permit the feed of the work to be performed. To temporarily lower the cams and sliding platen to a further extent, as for replacing matrices, the driving connection of cam shafts 40 and 46 to the cams may be through circular disks 60 eccentrically keyed to the shafts at 62, and received in circular recesses 64, eccentrically disposed within the cams, and, when the shafts 40 and 46 are rotated in direction adapted to transmit rotation from cam shaft to cam, the drive is through pawls 66 pivoted on the cams and spring pressed by springs 68 into engagement with teeth 70 on the disks 60. Upon opposite rotation of the cam shafts, as by clutching in and turning the normally declutched hand wheel 72, the springs 68 yield and disks 60 turn in the eccentrically disposed recesses 64 of the cams, thereby lowering the cams to the position shown in dotted lines in Fig. 7. Before operations are resumed after such maximum temporary opening, a second half turn of the rotation of disks 60 with respect to the cams is completed to return the cams to the full lines of Fig. 7.

The mechanically operated lifting of the press bed by the means described serves to bring same into position for application of the hydraulic closing mechanism, and the parts are shown in such position in Fig. 1. With the form shown, two rams, 76 and 78 work in cylinders 80 and 82. To permit the maximum temporary lowering of the press bed above described, the sliding platen 16 may have recesses 84 and 86 in its lower face, which recesses at such times receive the heads of rams 76, 78, as shown in Fig. 3, but it will be understood that such recesses and the platen lowering means comprising eccentrics 60 and pawls 66 may be dispensed with in case it is desirable to omit the provision for lowering the sliding platen through the extra distance.

The filling members or gag plates 92 and 94 for transmitting pressure from the rams to the sliding platen, with a minimum of ram movement, are mounted for horizontal reciprocative movement in slides 96 and 98 under the bottom of sliding platen 16, to be projected as indicated in Fig. 1, or to be retracted toward one another, as shown in Fig. 3.

The mechanisms for quickly moving the

gag plates 92, 94 in and out at the proper time, may take other forms than that shown for simple illustration of the principle involved, which comprises a sector 100 normally turning with cam shaft 40 and having separated partial sets 102, 104 of gear teeth adapted to intermittently engage the teeth of and actuate the gear 106 and to transmit multiplied rotational movement to the crank shaft 108 through the pinion 110, shaft 112, and gear train 116. The connecting rods 118 and 120 connect the gag plates 92 and 94 to the pivoted arms 122 and 124, which multiply the throw of the crank arms of crank shaft 108 and serve to alternately protract (Figs. 1 and 4) and retract (Fig. 3) the gag plates 92 and 94. The gag plates 92, 94 can be notched out as shown at 117, 117' to avoid interference with the pivoted arms and connecting rods. The platen is supported by the cams under each corner during in and out movement of the gag plates.

The valve mechanism for the supply to and outlet from the hydraulic cylinders of the oil or other fluid, like the gag plate actuating mechanism, is driven, with the construction shown, from shaft 40, the driving mechanism comprising sprocket wheel 130, sprocket chain 132, sprocket wheel 134, with which turns gear 136, and gear 138 actuated from gear 136.

Gear 136 has secured to it the cam plate 140 with a recess 142, and gear 138 carries a striker 144. These serve for operating the valve lever 146 by engagement with the roller 148 thereon. When recess 142 is opposite roller 148, striker 144 opens valve 150 against its spring to provide communication from the branched pipe 152 connected with the hydraulic cylinders to the outlet pipe 154. At other times the dwell part 140 of the cam on gear 136 holds the supply valve 156 open to provide communication from the supply pipe 158 to the pipe 152, leading to the cylinders. The valve operating mechanism for controlling the hydraulic rams is preferably of somewhat less height than as here shown for illustrating the principle of the invention, so as to keep it out of the way of direct horizontal feeding movement of the work.

The oil, water or other hydraulic fluid is preferably recirculated. Only a relatively small quantity is required because of the small movement of the rams, their movement and pressure being communicated to the sliding platen through the interposed filling members or gag plates, 92, 94, which are rapidly moved in and out as required.

In order to permit shaft 40 to be turned by means of hand wheel 72 as may be desired for imparting the maximum lowering movement to the sliding platen 16, without producing movement of the filling members 92, 94, which would interfere with dropping the sliding platen by engagement with the rams, and also without producing movement of the hy-

draulic valve mechanism, which would interfere by causing the rams to move, I preferably connect the hubs of sector 100 and sprocket wheel 130, as by a collar 100^a and provide the 5 spline parts 100^b and 130^b for detachably connecting said parts 100 and 130 to shaft 40. By shifting sector 100 and sprocket wheel 130, outwardly on shaft, 40 as by means of lever 101, shaft 40 can be freely turned without 10 actuating either the gag plates or the hydraulic valves. Lever 101 is moved back to re-engage these several parts with shaft 40 when normal operation is to be resumed, care being taken first to see to it that the spline 15 and spline ways are in alignment. This restores the original timing. Chain 132 has sufficient flexibility to permit such temporary side movement of sprocket wheel 130.

The preferred cycle of operation is dia- 20 grammatically indicated in Fig. 7, the various steps taking place in the order indicated below:

A—Mechanical lift, about 1/40 of a revolution.

25 B—Gag plates inserted, about 1/40 of a revolution.

C—Hydraulic lift, about 1/40 of a revolution.

D—Dwell under pressure, about 30/40 of 30 a revolution.

E—Hydraulic drop, about 1/40 of a revolution.

F—Gag plates withdrawn, about 1/40 of a revolution.

35 G—Mechanical drop, about 1/40 of a revolution.

H—Rest for feed of goods, 4/40 of a revolution.

Some of the outstanding advantages obtained with a press in accordance with my 40 invention are that the hydraulic power may be practically as high as desired and this pressure is uniformly distributed insuring uniform and accurate product, the short movement of the hydraulic rams enables the press to be speeded up and the product increased at the same time that the power for hydraulic 45 operation is minimized, the light, rapidly moving mechanical parts require but little power for their operation, full access can be readily had for changing die plates, etc., without disturbance of either the mechanical or hydraulic operating mechanism, wear and necessity for repairs and other maintenance 50 expense is extremely small and such wear as takes place is distributed practically evenly so that accuracy is practically independent of wear. The entire apparatus with accessory pumps, accumulators, etc., can be made 55 very compact, and is simple, durable and relatively inexpensive.

It will be understood that modifications coming within the scope of the following claims are included within the scope of my 60 invention.

I claim:

1. In a press, a movable press member, means for producing free movement of said member through a relatively considerable distance, and hydraulic means, applied to the movable member separately from the application thereto of the first named means, for producing the final pressing movement of said member, said hydraulic means being adapted to produce movement of said member through a shorter distance than the first named means. 70

2. In a press, a movable press member, mechanical means for producing free movement of said member through a relatively considerable distance, and hydraulic means, applied to the movable member separately from the application thereto of the mechanical means, for producing the final pressing movement of said member, said hydraulic means being adapted to produce movement of said member through a shorter distance than the mechanical means. 80

3. In a press, a movable press member, means for producing free movement of said member through a relatively considerable distance, hydraulic means for supplying the final pressure, and filling members movable into and out of place between said final pressure supplying means and said movable press member, whereby the final pressure is applied through substantially minimum travel of the means for supplying the final pressure. 90

4. In a press, a movable press member, mechanically operated means for producing free movement of said member through a relatively considerable distance, hydraulic means for supplying the final pressure, and filling members movable into and out of place between said hydraulic final pressure supplying means and said movable press member, whereby the final pressure is applied through substantially minimum travel of said hydraulic means. 100

5. In a press, a movable press member, means for moving said member through its greatest range of movement, means for producing free movement of said member through a lesser distance, and means movable through a still lesser distance for applying the final pressure. 110

6. In a press, a movable press member, manually operable means for moving said member through its greatest range of movement, mechanically operated means for producing free movement of said member through a lesser distance, and hydraulic means movable through a still lesser distance for applying the final pressure. 120

7. In a press, a movable press member, a hydraulic ram, a filling member, and means for interposing and withdrawing said filling member from between the movable press member and the ram. 125

8. In a press, a movable press member, a 130

hydraulic ram, a filling member, means for interposing and withdrawing said filling member from between the movable press member and the ram, and means for applying hydraulic pressure to the ram when the filling member is interposed.

9. In a press, a movable press member, having a cavity therein, a hydraulic ram in line with the cavity, a movable filling member adapted when in predetermined position to bridge the cavity, and means for interposing and withdrawing said filling member from between the movable member and the ram.

10. In a press, a movable press member, mechanically operated means for producing free movement of said member through a distance adapted to permit freely moving the work in the press, hydraulic means for imparting final pressure to the press member, filling members, and means for producing insertion of said filling members between the hydraulic means and the press member when the final pressure is applied and producing withdrawal thereof when the application of pressure has been completed.

11. In a column press comprising a head and a slidable platen, a plurality of cams operating in unison to produce free raising and lowering movement of the sliding platen, hydraulic ram means for supplying the final closing pressure to the slidable platen, filling members mounted for in and out movement below the sliding platen, and means for actuating the filling members whereby they are interposed between the sliding platen and ram means when application of final pressure is made.

12. In a press, an abutment press member, a press member movable toward and away therefrom, mechanical means for producing movement of the second member toward and away from the first member, filling means arranged for movement substantially at right angles to the press member movement, and hydraulic ram means operating through the filling means when in predetermined position to press the movable means forcibly against the abutment member.

13. In a press, an abutment press member, a press member movable toward and away therefrom, a cam under each corner of the movable press member, means for turning the cams in unison, a pair of hydraulic rams under the movable press member and within the inter-cam space, means operating in timed relation with the cams to produce alternate substantial filling or non-filling of space over the rams under the movable press member, and means operating in timed relation to the cams for alternately admitting actuating fluid to or permitting discharge thereof from the ram cylinders.

14. In a press a top abutment, a slidable

platen therebelow, means applied at the several corners of the platen for producing up and down movement thereof through a relatively considerable distance, and means separately applied to the platen and in the general neighborhood of the center thereof for applying closing pressure to the platen and producing movement thereof through a relatively smaller distance.

15. In a press a top abutment, a slidable platen thereunder and separate plural means for raising the slidable platen applied to the platen respectively in the neighborhood of the platen corners and in the neighborhood of the center thereof.

16. A column press comprising a base, guide columns, a head and slidable platen, a plurality of cams, means for operating said cams in unison to produce up and down movement of the platen, means for bodily lowering the cams to permit maximum lowering of the sliding platen as for replacement of dies, recesses provided in the under side of the sliding platen, hydraulic rams in line with said recesses, the rams being adapted to enter the recesses at periods of maximum lowering of the sliding platen, gag plates arranged to move in and out on the under side of the sliding platen below said recesses and serving, when in place between the platen and the rams, to transmit pressure therebetween, and means for supplying actuating fluid under pressure to the hydraulic rams when the gag plates are interposed between the rams and the sliding platen.

In testimony whereof, I have signed my name hereto.

JOHN J. CAVAGNARO.
